MINT JULEP CUP

Timothy C. Brown and William O. Waterhouse,
Louisville, Ky.

Application January 19, 1951, Serial No. 13,882

Term of patent 14 years

(Cl. D44—9)

To all whom it may concern:

Be it known that we, Timothy C. Brown and William O. Waterhouse, both citizens of the United States, residing in Louisville, Jefferson County, Kentucky, have invented a new, original, and ornamental Design for a Mint Julep Cup, of which the following is a specification, reference being had to the accompanying drawing, forming a part hereof.

Figure 1 is an elevational view of one side of a mint julep cup embodying our new design, the opposite side being identical in appearance except that it omits the representation of a horse-shoe; developed plan, of the design around the bottom portion of the cup.

We claim:

The ornamental design for a mint julep cup, as shown and described.

TIMOTHY C. BROWN.

WILLIAM O. WATERHOUSE.
